the last will and testament

By C. Snow & Co.

Attorneys,

UNITED STATES PATENT OFFICE.

JOHN E. GILCHRIST, DECEASED, LATE OF SOUTH BEND, WASHINGTON; BY CHARLES A. WERLEY, OF SOUTH BEND, WASHINGTON, EXECUTOR.

JACK.

Application filed July 1, 1925. Serial No. 40,897.

To all whom it may concern:

Be it known that JOHN E. GILCHRIST, deceased, formerly a citizen of the United States, residing at South Bend, in the county of Pacific and State of Washington, did invent a new and useful Jack, of which the following is a specification.

- This invention relates to lifting jacks, and aims to provide novel means whereby the lifting bar will be held in engagement with the lifting pinion cooperating therewith at all times, thereby insuring against lost motion, incident to the wearing of the teeth of the lifting bar or pinion.
- Another important object of the invention is to provide a removable member which may be readily inserted within the body portion to move the lifting bar laterally.
- A still further object of the invention is to construct the frame of the body portion in such a way as to increase the length of throw of the lever employed for rotating the pinion to operate the lifting bar.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:—

Figure 1 is a longitudinal sectional view through a jack constructed in accordance with the invention.

Figure 2 is a rear elevational view thereof, the lever being broken away.

Figure 3 is a transverse sectional view through the front portion of the jack taken on line 3—3 of Figure 1.

Figure 4 is a fragmental sectional view on line 4—4 of Figure 3.

Referring to the drawing in detail, the reference character 5 indicates the body portion of the jack which includes a base 6 on which the jack is supported.

The body portion is hollow and includes a pair of sections held together by means of the cap 7 positioned over the upper ends

of the sections and the bolts 8 that pass into the base 6, as shown by Figure 1.

The body portion also includes an enlarged portion 9 providing a housing for the shaft 10, pinion 11 and ratchet wheel 12, which pinion and ratchet wheel are mounted on the shaft 10 to rotate therewith.

Pivots supported within the housing is a pawl indicated at 13 that cooperates with the ratchet wheel 12, the same being held in position by means of the spring member 14, so that as the pinion 11 is moved to operate the lifting bar, to be hereinafter more fully described, the ratchet wheel 12 together with the pawl 13 will operate to lock the lifting bar against movement.

The lifting bar is indicated at 15 and is provided with teeth 16' that are engaged by the pinion 11 to lift the bar. Disposed between one wall of the housing 9 and the outer edge of the lift bar 15 is a removable plate 16 provided with an outwardly extended upper flange 17 designed to rest over the upper portion of the housing 9 to support the plate in an elevated position. The lower end of the plate is provided with a flange 18 that engages the inner surface of the front wall of the housing to hold the plate normally in spaced relation with the housing.

The space between the plate 16 and wall of the housing, is especially adapted for the reception of a shim or spacing plate such as indicated at 22 adapted to be positioned to move the plate 16 into close engagement with the forward edge of the lifting bar 15 so that lost motion due to wear between the teeth of the pinion 11 and teeth 16' of the lifting bar will be obviated, and the bar 15 moved into close engagement with the pinion 11.

The reference character 19 indicates the operating lever which is supported on the shaft 10 to rotate the ratchet wheel 12 which in turn transmits movement to the shaft 10 and pinion 11 carried thereby. A latch member indicated at 20 is carried by the lever 19 and operates a suitable pawl mechanism that engages the ratchet wheel 12 and transmits movement of the lever 19 to the ratchet wheel.

As shown, the lower portion of the housing 9 is cut away to allow the lever 19 to move to a position in close proximity to the body portion, thereby greatly increasing the 5 length of the stroke of the lever.

The lower end of the lifting bar 15 extends outwardly providing a lifting arm 21 which may be positioned under an article 10 to be lifted when it is desired to elevate devices disposed in close proximity to the ground surface or surface on which the jack 15 is being used.

When the jack becomes worn and lost motion occurs between the lifting bar 15 and the pinion 11, the cap 7 is lifted from its position as shown by Figure 1 and a shim 16 or spring plate such as indicated at 22 positioned between the plate 16 and inner surface of the housing 9 to move the plate 16 into engagement with the lifting bar 15. It is obvious that the size of shim may be regulated according to the space between the lifting bar and plate 16 caused by wear.

I claim:—

1. A lifting jack comprising a body portion a housing forming a part of the body portion, a lifting bar movable through the body portion and having teeth formed along one of its edges, a pinion meshing with the 25 teeth of the lifting bar, means for operating the pinion to move the lifting bar vertically, a bearing plate supported within the housing and contacting with the lifting bar, and removable means positioned between the 30 bearing plate and body portion for moving the bearing plate into engagement with the lifting bar.

2. A lifting jack comprising a body portion, a housing forming a part of the body portion, a vertically movable lifting bar, 40 operating through the housing, means for operating the lifting bar, a bearing plate supported within the housing and contacting with the vertically movable lifting bar, and a shim positioned between the bearing plate and housing to move the bearing plate into close engagement with the vertically 45 movable lifting bar.

3. A lifting jack comprising a body portion, a housing forming a part of the body 50 portion, a vertically movable lifting bar operating through the body portion, said lifting bar having teeth, a pinion cooperating with the teeth to move the lifting bar vertically, a bearing plate having flanges 55 formed at its ends, and a spring plate adapted to be positioned between the flanges to move the bearing plate into engagement with the lifting bar.

4. A lifting jack comprising a body portion, a housing forming a part of the body portion, a lifting bar movable through the body portion, a bearing plate having flanges formed at its ends, one of said flanges adapted to engage the inner surface of the 60 housing to hold the bearing plate in spaced relation with the housing, and a shim adapted to be positioned between the bearing plate and housing to move the bearing plate into close engagement with the vertically 65 movable member.

CHARLES A. WERLEY,
*Executor of the Last Will and Testament
of John E. Gilchrist.*
